AUTOMOBILE ROOFTOP AIR DEFLECTOR

Louis L. Borick, 17527 Corinthian Drive,
Encino, Calif. 91316

Filed Feb. 23, 1966, Ser. No. 1,192

Term of patent 14 years

(Cl. D14—6)

FIG. 2

FIG. 3

FIG. 4

FIG. 5

FIGURE 1 is a perspective view of an automobile rooftop air deflector, showing my new design;

FIGURE 2 is a broken front elevational view thereof;

FIGURE 3 is a broken rear elevational view thereof;

FIGURE 4 is a broken top plan view thereof;

FIGURE 5 is a broken bottom view thereof; and

FIGURE 6 is a side elevational view thereof.

I claim:

The ornamental design for an automobile rooftop air deflector, substantially as shown and described.
